DESIGN FOR A COMBINED TEMPLE AND TEMPLE SUPPORT FOR AN OPHTHALMIC MOUNTING

Edward M. Splaine, Southbridge, Mass., assignor to American Optical Company, Southbridge,
Mass., a voluntary association of Massachusetts

Application October 24, 1935, Serial No. 59,204

Term of patent 14 years

To all whom it may concern:

Be it known that I, Edward M. Splaine, a citizen of the United States, residing at Southbridge, in the county of Worcester and State of Massachusetts, have invented a new, original, and ornamental Design for a Combined Temple and Temple Support for an Ophthalmic Mounting, of which the following is a specification, reference being made to the accompanying drawing, forming a part thereof.

Fig. 1 is an enlarged perspective view of a combined temple and temple support for an ophthalmic mounting embodying my design;

Fig. 2 is an enlarged partial front view of the same; and

Fig. 3 is an enlarged partial plan view of the same.

The characteristic features of my design are shown in full lines.

I claim:

The ornamental design for a combined temple and temple support for an ophthalmic mounting substantially as shown and described.

EDWARD M. SPLAINE,
